UNITED STATES PATENT OFFICE.

HILDA KOSKELA, OF LE ROY, OHIO.

CLEANING COMPOUND.

No Drawing.

Application filed November 18, 1924. Serial No. 750,678.

To all whom it may concern:

Be it known that I, HILDA KOSKELA, a citizen of Finland, residing at Le Roy, in the county of Medina and State of Ohio, have 5 invented certain new and useful Improvements in Cleaning Compounds, of which the following is a specification.

This invention relates to certain improvements in cleaning compounds and it is an 10 object of the invention to provide a novel and improved compound of this general character which can be employed with equal facility in connection with textiles and metals.

15 It is also an object of the invention to provide a novel and improved compound of this general character which is particularly advantageous for use in the removal of ink stains, varnish, rust and other stains.

20 My improved compound consists of:

Sour milk-----	1 quart.
Sodium chloride-----	7 ounces.
Vinegar-----	1 pint.
Lemon juice-----	1 pint.
25 Alcohol-----	1 pint.
Ethyl, substantially 95%.	

In making my compound, the salt is first mixed well with the sour milk after which 30 the vinegar is added. After thoroughly shaking such admixture, the lemon juice is added together with the alcohol.

This mixture or compound operates effectively to remove all stains from dry goods and kindred textile material and also effectively 35 cleans copper, brass, silver, nickel, and other metal or plateware.

In removing stains from dry goods or the like the same is maintained submerged in my improved compound for a period between fifteen or forty-five minutes whereupon the article is washed with soap and hot water. If the stain is not removed at the first operation the same is repeated. In taking out ink spots, if the spot is fresh the 40 goods is first washed out with warm water to remove as much of the stain as possible and then the goods is submerged in the mixture for a period between fifteen to forty-five minutes and then washed out with hot 45 boiling water and soap. In cleaning metals, the compound is applied with a soft cloth and then rubbed dry with a soft dry cloth.

50 I claim:

A cleaning composition consisting of an admixture of sour milk, 1 qt., sodium chloride, 7 ozs., vinegar, 1 pt., lemon juice, 1 pt., and alcohol, 1 pt.

In testimony whereof I hereunto affix 60 my signature.

HILDA KOSKELA.
